Inventor
Harry R. Van Deventer

UNITED STATES PATENT OFFICE.

HARRY R. VAN DEVENTER, OF NEW YORK, N. Y., ASSIGNOR TO RADIO PATENTS CORPORATION, OF NEW YORK, N. Y., A CORPORATION OF NEW YORK.

TELEPHONE ATTACHMENT FOR PHONOGRAHPS AND THE LIKE.

Application filed June 18, 1923. Serial No. 646,058.

This invention relates to attachments for phonographs or the like, particularly to an attachment whereby a telephone receiver may be connected to the ordinary phonograph instrument so as to produce what is commonly termed a "loud speaker".

In the pending application of R. E. B. Wakefield, Serial No. 630,127 filed April 5, 1923, is shown and described an attachment of this character. The present invention consists of an improvement in the construction of such a device.

One of the objects of this invention is to provide a telephone instrument that may be readily attached to many different makes of phonographs. Another object is to provide a telephone instrument in which the case or cap thereof also forms the supporting base on which the instrument is mounted. There are other objects and advantages that will hereinafter more fully appear.

In the accompanying drawings,

Figure 1 is a front elevation illustrating the invention, and

Figure 2 is a side view of the same.

For the sake of illustration, the invention is shown as applied to an ordinary talking machine of the "Victrola" type. This employs a reproducer indicated in the drawing by the numeral 1 to which is connected the usual horn 2.

In accordance with the Wakefield application hereinbefore mentioned, the ordinary reproducing needle of the reproducer is removed from the holder 3 and the end of a wire 4 connected instead. The inner end of this wire is connected at 5 to the diaphragm of a telephone receiver, which diaphragm is indicated by the dotted line 6.

The rear casing 7 contains suitable telephone receiver mechanism, and as this may be of any desired type, I do not show and describe the same.

The foregoing arrangement forms part of the Wakefield invention hereinbefore mentioned, and is shown here merely for purposes of illustration.

It is necessary in this or any type of telephone receiver to provide the same with a front member or cap 8. In the receivers heretofore known this cap has served mere-

ly to close the front of the telephone receiver, the complete receiver being then placed in a support or housing.

My invention consists in providing the receiver cap with an integral foot member 9 constituting the support for the entire instrument and making unnecessary any other supporting means.

The cap portion 8 and foot 9 may be secured together in any suitable manner but are preferably made of one piece and are usually made of bakelite or a similar insulating substance.

It will be observed that by the method of construction just described, the distance from the record table or support 10 upon which the receiver is placed and the center point 5 of the diaphragm is always definitely maintained, and that the necessity of providing a support for the body portion 7 of the receiver is obviated.

It will also be noted that by means of thumb screws or other suitable means 11 and 12, the telephone receiver may be adjusted vertically to enable the wire 4 to be properly connected to reproducers that are various heights above the table or support 10.

I claim:

1. In a sound producing device, the combination with a phonograph reproducer embodying a needle holder, a telephone receiver embodying a vibratory member and an actuating coil mounted in operative proximity thereto, means for transmitting vibrations from said vibratory member to said needle holder, and a cap for said receiver adapted to hold said vibratory member in operative position and also serving as a support for the entire receiver.

2. In combination a phonograph having a reproducer and a record table, a telephone receiver, having a diaphragm cap forming a support for the receiver, a connection between said reproducer and said telephone receiver, and means carried by said diaphragm cap adapted to engage said record table and adjust the relative position of said reproducer and receiver, substantially as described.

In testimony whereof I affix my signature.

HARRY R. VAN DEVENTER.
